UNITED STATES PATENT OFFICE.

THOMAS E. PURCELL, OF PITTSBURGH, PENNSYLVANIA, ASSIGNOR TO INTERNATIONAL COMBUSTION ENGINEERING CORPORATION, A CORPORATION OF DELAWARE.

FURNACE CONSTRUCTION.

Application filed July 30, 1925. Serial No. 46,966.

This invention relates to furnace constructions and is particularly useful in furnaces adapted for the burning of pulverized fuel in suspension.

5 One of the primary objects of the invention is to provide a simple and effective furnace wall which may be readily built and maintained.

10 Another object of the invention is to provide a furnace wall construction in which provision is made for the admission of combustion air in a novel and simple manner.

15 More specifically my invention aims to substitute a simple and inexpensive wall in substitution for the hollow wall construction now frequently employed in installations burning pulverized coal.

20 In general my invention resides in the novel features and combination of parts to be more particularly described hereinafter.

25 How the foregoing, together with such other objects as may hereinafter appear, or are incident to my invention, are realized, is illustrated in preferred form in the accompanying drawings, wherein

Fig. 1 is a vertical section thru a portion of a furnace embodying my improvements, the section being taken on the line 1—1 of Fig. 3;

30 Fig. 2 is a vertical section thru a portion of the wall of Fig. 1 drawn on an enlarged scale, the section being taken on the line 2—2 of Fig. 3;

35 Fig. 3 is a horizontal section thru a portion of the wall of Fig. 1, drawn on an enlarged scale;

40 Fig. 4 is a section taken on the line 4—4 of Fig. 3, and

45 Fig. 5 is a horizontal sectional view illustrating a corner of the furnace structure.

The invention is particularly useful in connection with the front walls of powdered coal burning installations and will be described in connection therewith, altho it may be used elsewhere to advantage.

Referring now to Fig. 1, the furnace is indicated as a whole by the reference letter A, the combustion chamber having an outlet 7 in the upper part thereof over which extend 50 the boiler tubes 8, it being understood that any type boiler may be employed. The furnace is composed of the front wall B, the side walls C, the rear wall (not shown), the hop-

per shaped bottom D, the suspended arch E and the throat F which forms the outlet 7. 55

Specifically considering the front wall, it is composed of refractories, to be described; and the outer metallic casing 9 secured to and supported by the vertical buck-stays 10; and the horizontal beams 11 which latter are secured to the buck-stays in the manner indicated in

Fig. 2. The refractory portion of the wall consists of a base portion 12 composed of bricks or the like and carried by the structural work 13; the sheathing 14; and a tier 15 composed of two kinds of bricks, namely the holding tile 16 and the filler bricks 17. The filler bricks 17 are of L shaped as indicated in Fig. 3 with a vertical groove 18 along one edge adapted to engage with the head 19 of vertically extending holding castings 20 secured to the buck-stays as shown in Fig. 3. The spacing of the holding castings 20 and the dimensions of the bricks 17 are such as to provide a gap 21 between the legs of adjacent bricks 70 60 65

in order that these bricks may be readily assembled, removed or replaced as the case may be.

The holding tiles 16 are of substantially similar construction with the exception that 80 the dimensions of the bricks, with reference to the spacing of the holding members 20 are such that a pair of these bricks in effect constitutes a U. These bricks are formed so as to engage the heads 19 of the holding castings in the manner already described. The tier 15 comprises the course of the bricks 16, a number of courses of the bricks 17, a course of the bricks 16, etc. When the wall is completed it will be seen that the bricks 16 cannot 90

fall out of place but are held by the holding castings 20. The bricks 17 are held in place by virtue of the fact that they rest upon one another and are in effect carried by the holding tile 16. The construction of the bricks 16 and 17 is such as to provide vertical ducts 22 within the wall, the gaps 21 formed by the bricks 17 constituting inlet or delivery openings from the ducts into the interior of the combustion chamber. Combustion air is 100 supplied to the ducts thru a plurality of inlet openings 23, which inlets are damper controlled. At the top and bottom of each duct is a larger damper controlled inlet 24.

It will be seen that the wall can be readily 105 built and maintained and is comparatively

simple in construction. Except at certain points all of the bricks 17 and all of the bricks 16 may be counterparts of one another which tends toward cheapness and ease of assembly and repair. Furthermore, the wall can expand and contract freely. The sheathing 14 is provided merely for the purpose of protecting the metallic casing from the heat and flames because of the presence of the openings 10 thru the wall.

The side walls, have the same metallic outer casing 9 and the sheathing 14.

At points opposite the buck-stays 10 there are channels 25 which constitute a part of the metallic casing. Metallic strengthening and attaching strips 26 are interposed between the base of the holding castings 20 and the channels 25. At points intermediate the buck-stays, strips 26 are interposed between the metallic casing and the base of the holding castings 20 and blocks 27 are interposed between the horizontal channels 11 and the metallic casing at intervals, which holding casting is provided with web portions 28 for purposes of strength and for holding the sheathing. If desired asbestos mill board 29 or the like is interposed between the metallic casing and the sheathing. Fire clay is preferably used between the faces of adjacent bricks and there is an expansion joint 30 between the side wall and the front wall.

What I claim is:

1. A furnace wall structure including substantially vertically extending holding members, and a refractory wall composed of adjacent reversely placed L-shaped bricks adapted to engage the holding members and so disposed that pairs of bricks cooperate to provide a duct.

2. A furnace wall structure including substantially vertically extending holding members, and a refractory wall composed of adjacent reversely placed L-shaped bricks adapted to engage the holding members, certain of the bricks having a dimension such as to provide a gap between the legs of pairs of bricks.

3. A furnace wall structure including substantially vertically extending holding members, and a refractory wall composed of adjacent reversely placed L-shaped bricks adapted to engage the holding members and so disposed that pairs of bricks cooperate to pro-

vide a duct, said holding members engaging the bricks at the sides thereof adjacent their outer faces.

4. A furnace wall structure including an outer shell, structural work therefor, a lining for the shell, vertically extending laterally spaced brick holding members, and a refractory wall composed of bricks arranged in horizontal pairs, each pair lying between adjacent holding members, and said holding members interlocking with the bricks, and the bricks being so shaped and disposed that a pair thereof cooperate to form a channel.

5. A furnace wall structure including an outer shell, structural work therefor, a lining for the shell, vertically extending laterally spaced brick holding members, and a refractory wall composed of bricks arranged in horizontal pairs, each pair lying between adjacent holding members, and said holding members interlocking with the bricks, and the bricks being so shaped and disposed that a pair thereof cooperate to form a channel, and said shell and lining having air inlet means to the channels formed by the bricks.

6. A furnace wall structure including an outer shell, structural work therefor, a lining for the shell, vertically extending laterally spaced brick holding members, and a refractory wall composed of bricks arranged in horizontal pairs, each pair lying between adjacent holding members, and said holding members interlocking with the bricks, and the bricks being so shaped and disposed that a pair thereof cooperate to form a channel whereby ducts are provided within the wall.

7. A furnace wall structure including an outer shell, structural work therefor, a lining for the shell, vertically extending laterally spaced brick holding members, and a refractory wall composed of bricks arranged in horizontal pairs, each pair lying between adjacent holding members, and said holding members interlocking with the bricks, and the bricks being so shaped and disposed that a pair thereof cooperate to form a channel whereby ducts are provided within the wall, together with means whereby air may be admitted to the ducts.

In testimony whereof, I have hereunto signed my name.

THOMAS E. PURCELL.
